UNITED STATES PATENT OFFICE.

EDWIN GEO. WARNER, OF CHICAGO, ILLINOIS.

AUTOMOBILE-THEFT ALARM.

1,367,337.

Specification of Letters Patent.

Patented Feb. 1, 1921.

Application filed May 19, 1920. Serial No. 382,483.

To all whom it may concern:

Be it known that I, EDWIN GEO. WARNER, a citizen of the United States, residing at Chicago, in the county of Cook and State of Illinois, have invented new and useful Improvements in Automobile-Theft Alarms, of which the following is a specification.

The object of the invention is to provide comparatively inexpensive and relatively simple means adapted to be applied as an attachment to a motor vehicle of any of the well-known commercial types as a means of giving an alarm which is distinguishable from other forms or types of signals, to indicate the surreptitious removal or driving of a machine equipped with a device to warn the owner and to guide officers of the law in following the thief; and with this object in view, the invention consists of the construction and combination of parts of which a preferred embodiment is shown in the drawings, wherein:—

Figure 1, is a view of the alarm apparatus applied in operative position to a motor vehicle.

Fig. 2, is a plan view of the same.

Fig. 3, is a front view of same.

Fig. 4, is a detail sectional view showing the means whereby motion is communicated to the bell and hammer.

Fig. 5, is a view of the key holder and bell attachment.

Fig. 6, is a detail view partly in section of the connection between the follower and the bell hammer.

Fig. 7, is a detail perspective view of the follower actuating plug or pin.

Fig. 8, is a similar view of the bell hammer.

Fig. 9, is a similar view of the key.

Fig. 10, is a detail sectional view of the key on the plane indicated by the line 10—10 of Fig. 9.

The apparatus is adapted for actuation by the drive or motor shaft of the vehicle which is indicated at 10 in the arrangement illustrated in the drawing, and embodies an alarm sounding means such as a reciprocable hammer 11 adapted for terminal contact with a plate 12 or the equivalent thereof suitably suspended in an inconspicuous position beneath the floor of the car body as indicated in Fig. 3 of the drawing, and a hammer actuating means driven by the motor shaft and capable of location in operative or inoperative relation with the

motor shaft, to the end that when not required or when the machine is occupied the alarm mechanism may be disconnected, whereas when the vehicle is to be left temporarily unoccupied, the alarm mechanism may be connected so that the operation of the machine by unauthorized persons, not having the means to un-set the alarm, will be communicated by the sounding of the bell or equivalent audible signal which should be of such a nature and construction as to be readily distinguishable from ordinary vehicle bells, fire bells and like alarms which are used with authority, for example by municipal officers.

In the illustrated embodiment of the invention, the alarm mechanism embodies a driven shaft 12' connected with the motor drive shaft 10 by means of a chain 13 traversing the sprocket wheels 14 and 15, said driven shaft carrying a segment or milled gear 16 for operation in connection with a rack 17 carried by the bell hammer 11, said hammer being yieldably held in striking position by means of a spring 18 so that when said shaft 12' is rotated, it alternately retracts the hammer by the engagement of the gear 16 with the rack 17 in opposition to the tension of the spring 18 and thus hoists the hammer to be driven forward in contact with the bell as indicated in Fig. 3.

The rack with which the hammer rod 11 is provided is formed as a part of a slide 19 having lateral longitudinal grooves 20 for engagement by lips 21 formed on a guide head 22 which in turn constitutes an element of a follower 23 of which the perforated barrel 24 is engaged by a stem 25 forming a pin or plug 26. The block is revolvably mounted in a tubular casing 27 permanently substantially secured to and depending from the under surface of the floor 28 of the car or a like convenient support and the upper end of said block is notched to form a head 29 of which the end side constitutes a shoulder 30 to bear upon a shoulder formed by the reduced lower portion of the door of the casing, while revolvably mounted in the upper or large portion of the door section is a thimble 31 held from displacement by a key hole plate 32 which may be secured to the upper surface of the floor of the car and is cut away as indicated at 33 to provide for the introduction of a key 34 in which the key socket 35 seats operatively the block or

- pin 26. Preferably the socket and key are of unusual shape as for example longitudinally ribbed or corrugated so as to avoid the possibility of using an ordinary knife blade 5 or its equivalent in lieu of a key and also preferably the lateral edges of the key as indicated particularly in Fig. 10 are reduced or sharpened on their lower or inner ends, and one end of the key may also be cut away 10 to provide a preferred construction to which a key socket 36 in the upper end of the actuating block or pin 26 is adapted to increase the difficulty of surreptitious adjustment of the said block or pin after it has been set by 15 the owner of the car to give the intended alarm.

Under normal conditions, when the car is occupied and is being driven by the owner or with the authority of the owner, 20 the rack by which motion is communicated to the alarm sounding element or hammer 11 is withdrawn from engagement with the mutilated gear 16 by backing the reversely shifting block or pin 26 to retract the follower 23. When the machine is to be locked, the proper key may be introduced 25 into the socket in the thimble 31 until its extremity engages the socket 36 in the actuating block or pin, whereupon the latter 30 may be turned to advance the follower to cause engagement of the rack with the pinion 16 so that any revolution of the motor shaft of the car will result in the alternate contraction and release of the alarm sounding 35 element and hence the giving of the alarm to notify those within hearing that the car is being moved without the authority of the owner.

A plate 37 may be mounted pivotally as 40 at 38 upon the key hole plate 32 to exclude dust from the key socket and obviously the key hole plate may be arranged in the floor of the car beneath the mat ordinarily employed so as to be inconspicuous and un- 45 likely to attract the attention of any one desiring to move the car without the authority of the owner. The mechanism beneath the car floor and constructed and arranged as above indicated, may be com- 50 pactly disposed so as to attract little or no attention and obviously may be applied to a car of any ordinary commercial form without in any way interfering with the usual functions of the parts.

55 The invention having been described, what is claimed as new and useful is:—

1. An alarm mechanism for motor vehicles having a reciprocable alarm sounding device, a mutilated gear and rack mechanism 60 having power to communicate motion to the sounding element, the gear being actuatable by the vehicle motor, and means for positioning the elements of the gear and rack mechanism in and out of operative relation.

2. An alarm mechanism for motor vehicles having a reciprocable alarm sounding element provided with a rack and driven shaft actuatable by the driving shaft of the vehicle motor and provided with a mutilated gear for actuating the said rack and means 70 for moving the rack into and out of operative relation with said gear.

3. An alarm mechanism having a spring actuated reciprocable alarm sounding element provided with a rack, a mutilated gear 75 actuatable by the vehicle motor for periodically retracting the said sounding element in opposition to the tension of the actuating spring, and means including a follower having a guide head engaged with said rack for 80 positioning the latter relative to the mutilated gear.

4. An alarm mechanism for motor vehicles and spring actuated reciprocable alarm sounding element and means for periodically 85 retracting the same including a motor driven mutilated gear for engagement with a rack connected with said reciprocable element, a follower having a guide head in sliding engagement with said reciprocable element 90 and an actuating block or pin for moving the follower to determine the position of the rack relative to the mutilated gear and means for communicating motion to the actuating block or pin. 95

5. An alarm mechanism for motor vehicles having a spring actuated alarm sounding element, provided with a rack and motor driven mutilated gear for engagement with said rack to retract the 100 reciprocable element, said rack being movable into and out of operative relation with the gear in combination with an axially moving follower for sliding engagement with said rack, a follower actuated pin or block mounted for rotary movement and for threading engagement with the follower and an independent revoluble thimble disposed in concealing relation with the block or pin and having a key socket 110 in registration with a key socket in the adjacent end of said block or pin. 115

6. An alarm mechanism for motor vehicles having in combination with a reciprocable motor driven alarm sounding element and means for disposing said element into and out of operative relation with the motor driven gears, a follower connected with said alarm sounding element and a revoluble actuating pin or block operatively connected with the follower, a thimble arranged in co-axial relation with the block or pin and provided with an axle key socket said block or pin being also provided with a key seat for registration with 125 the key socket of the thimble.

In testimony whereof I affix my signature.
EDWIN GEO. WARNER.
